COMBINATION TUBE WORKING TOOL AND REAMER

Filed Sept. 9, 1949

UNITED STATES PATENT OFFICE

2,630,028

COMBINATION TUBE WORKING TOOL
AND REAMER

Robert D. McIntosh, River Forest, Ill., assignor to
The Imperial Brass Manufacturing Company, a
corporation of Illinois

Application September 9, 1949, Serial No. 114,709

6 Claims. (Cl. 77—73)

1

This invention relates to a tube working tool and more particularly to a hand operated tool for reaming relatively small tubes.

A general object of the invention is to provide an improved tube working tool.

A more particular object of the invention is to provide a tube working tool having an elongated body member adapted to be held in the hand of a workman and a reamer pivotally mounted in the body member to have an inoperative position in which it lies flat against the body member and an operative position extending longitudinally of the body member from an end thereof.

Another object is to provide a tube working tool having a body member adapted to be held in the hand of a workman and a reamer pivotally mounted in said body member to be swingable from an inoperative to an operative position, and vice versa, the reamer and body member being formed with cooperating means and with a spring resiliently retaining the reamer in both inoperative and operative positions, the cooperating means being so formed that the reamer snaps into rigid operative position as an incident to mere pivoting thereof to the limit of its movement in one direction, while release from operative position requires longitudinal movement of the reamer away from the body member and against the action of the spring.

Another object of the invention is to provide a tube working tool having a body member adapted to be held in the hand of a workman with a recess in one corner of the body opening to an end and side thereof and a reamer pivotally mounted on the body member at the recess having a locking portion extending into said recess and adapted to be received in a channel in the body member within the recess to lock the reamer in operative position projecting longitudinally from the end of the body member.

Another object is to provide a tool wherein the reamer is mounted for pivotal movement and axial movement longitudinally of the body member, whereby the reamer may be locked in operative position.

Another object is to provide a tool of the character described having a spring urging the reamer member into locking position and also acting to retain the reamer member in inoperative position.

Other objects and advantages of the invention will be apparent from the following specification and drawings, in which:

Fig. 1 is a side elevational view of a tube working tool constructed in accordance with the in-

2

vention, underlying parts being shown in broken lines and the reamer being shown in inoperative position in solid lines, and in operative position in broken lines.

Fig. 2 is an end elevational view of the tool taken from the left in Fig. 1.

Fig. 3 is an enlarged fragmentary bottom plan view showing the reamer in operative position.

Fig. 4 is a fragmentary longitudinal section taken along the line 4—4 of Fig. 3.

Fig. 5 is a fragmentary horizontal section along the line 5—5 of Fig. 4.

Fig. 6 is a fragmentary vertical transverse section along the lines 6—6 of Fig. 4.

Tools of the type illustrated in Fig. 1 are commonly used for working with relatively small tubing of copper, aluminum, steel and the like. Generally after a tube has been cut small burrs or even a flange are left in the bore of the tube, and it is necessary for the workman to clear the flange or burrs from the tube with a reamer before a connection to a fitting can be made. While a separate reamer tool may be carried by the workman in his tool box or in his pocket, it is much more convenient to incorporate the reamer and the cutting device in a single tool, and the reamer herein disclosed is particularly adapted for such construction. Whether the reamer comprises part of a compound tool or is a separate instrument, the reamer blade should be movable to an inoperative, out of the way position when the reamer is not in use in order to protect the workman and the working edges of the reamer blade and to facilitate manipulating the tool where a compound tool is used.

Referring now more particularly to the drawings, the improved tool is shown as comprising a body member designated generally at 10 and having mounted thereon a reamer designated generally at 11. The body member is elongated so that it may readily be held in the hand of a workman and so that pressure can be applied by the workman when he reams the burrs from the bore of a tube. While, as pointed out above, the reamer may comprise a separate tool, the preferred shape of the body member of the reamer readily adapts the reamer for use as a part of a compound tool, and the reamer is shown herein as comprising part of a compound tool wherein the body member also carries tube cutting apparatus.

In Fig. 1 the body member 10 is shown as comprising a U-shaped portion 12, an end wall 12a of which carries a pair of rollers 13 and 14 for supporting a tube which is to be cut. Each of

these rollers has a notch, as shown at 13a in Fig. 2, for receiving a flange which is sometimes formed on the end of a tube.

At the other end of the body member 10 is a shank portion 15 providing a mounting and bearing for a movable cutter holding member 16 which carries a rotatable cutting disc 17. The member 16 is movable longitudinally of the shank by means of a rotatable handle 18 for cutting a tube which is supported on the rollers 13 and 14. The portion 12b intermediate the ends will for convenience hereinafter be referred to as the base.

The body member has a recess 20 at one corner thereof opening through both the end and the base of the body member. Oppositely disposed wall portions 21 and 22 of the body member form the sides of the recess 20. The wall portions 21 and 22 have key-hole slots 21a and 22a therein positioned with the rounded portions thereof near the end of the body member and with the narrow rectangular portions thereof extending away from said end, as best shown in Figs. 1 and 4. An axle member 25 is mounted in the slots 21a and 22a and extends between the wall portions 21 and 22, said axle member having at least its bearing portions formed with a rectangular, transverse cross section (see Fig. 4) and being rotatable in the rounded portions thereof and slideable longitudinally of the body member 10 in the narrow rectangular portions of the slots.

The reamer 11 has a reaming portion comprising a wedge-shaped blade 26 with ears 27 and 28, adapted to be grasped for manipulation of the reamer, bent at right angles to the blade near the base thereof, and a locking portion comprising a pair of L-shaped projections 30 and 31 extending axially of the reamer in the opposite direction from the blade. The projections 30 and 31 are nonrotatably mounted on the axle member 25 in the recess 20 closely adjacent the wall portions 21 and 22, so that the reamer may be pivoted between an inoperative position, shown in solid lines in Fig. 1, and an operative position shown in broken lines in Fig. 1.

A leaf spring 35 is mounted on the outside of the end wall 12a of the body member by means of a stud 36, and the spring extends down into engagement with the axle member 25. In order to increase the tension of the spring, a tensioning member 37 also is secured by the stud and overlies the spring throughout a portion of its length. The spring constantly urges the axle member 25 toward the narrow portion of the slots.

At the bottom of the recess 20, the body member is provided with a U-shaped channel to receive the projections 30 and 31 when the axle member 25 is in the narrow portion of the key-hole slots as illustrated. This channel is shown best in Fig. 6 and comprises a base or connecting groove 38 and grooves 39 and 40 forming the arms of the U-shaped channel and opening through the base 12b of the body member 10. Above the base 38 of the channel (speaking with respect to the parts when in the position of Fig. 1) is a shoulder 41 formed by locating the base groove 38 of the U-shaped channel downwardly from the upper wall of the recess. The space above this shoulder 41 gives clearance for the portions 30 and 31 of the locking part of the reamer when the reamer is pivoted into and out of operative position.

The tool is normally carried with the reamer in inoperative position as shown in Fig. 1. When it is desired to move the reamer to operative position, shown in broken lines in Fig. 1 and in solid

lines in Fig. 4, it is only necessary to impart rotation to the reamer, no manual longitudinal shifting of the reamer being necessary. In such rotational movement of the reamer, the corners a of the projections 30 and 31 bear against the bottoms of the grooves 39 and 40 and serve to cam the axle member 25 outwardly of the rectangular portion of the key-hole slots into the rounded portion thereof. This camming action is made possible because there is nothing to restrain outward movement of the corners b of the projections. Once the axle member 25 is in the circular portion of the key-hole slots it and the reamer are free to rotate until the edges c of the projections strike the shoulder 41. Because of slight play created by a difference in the width of the axle member 25 and the diameter of the rounded portion of the key-hole slots, continued rotation of the reamer after the edges c have contacted the shoulder 41 results in a further cam action moving the axle member 25 outwardly very slightly to provide sufficient clearance to permit the edges c to slip past the shoulder 41 and into the base groove 38 of the channel. Once the edges c are past the shoulder 41, the spring 35 forces the projections 30 and 31 into the channel and the axle member 25 into the rectangular portion of the keyhole slots for the axle member 25 now is positioned with its width extending parallel with the rectangular portions of the key-hole slots.

The camming action above described for the corners a of the projections 30 and 31 is obtained because the distance from the corners a to the axle member 25 is greater than the distance from the inner ends of the key-hole slots to the portion of the wall engaged by the corners a as the blade is swung from inoperative to operative position. This construction of the projections 30, 31 and the camming action that results has a second purpose or function, namely, that of tending to retain the reamer blade in inoperative position.

In contrast to the swinging of the reamer from inoperative to operative position solely by application of a force rotating the reamer about its axle member, return of the reamer from operative to inoperative position can be effected only after the reamer is first shifted longitudinally against the action of the spring 35 and in a direction opposite to the reaction of the reamer during a reaming operation. This longitudinal shifting of the reamer is readily accomplished by grasping the ears 27 and 28 between the thumb and index or middle finger, applying a longitudinally outward pull, and then following through with a rotational movement of the reamer.

The camming action obtained at the start of the movement of the reamer from inoperative to operative position is not obtained. This is believed due to the fact that the shoulder 41 blocks movement of the edges c when the corners d on the projections 30 and 31 attempt to cam the axle member 25 outwardly. Stated another way, the edges c are not free to move in an outward arc as were the corners b. Only after the corners c have by longitudinal movement of the reamer cleared the shoulder 41 is the reamer free for swinging to inoperative position. Under these circumstances, there is absolutely no danger or possibility that the reamer blade will during use be accidentally swung out of operative position with the possible injury that might result, by such sudden collapse of a tool, to the workmen or to the tubing. A cut-away portion 42 in the base of the body member 10 insures that the reamer blade does not

project outside the surface of the base when the blade overlies the body member.

While I have shown and described certain embodiments of my invention, it is to be understood that it is capable of many modifications. Changes, therefore, in the construction and arrangement may be made without departing from the spirit and scope of the invention as disclosed in the appended claims.

I claim as my invention:

1. In a combination tube working tool and reamer comprising a body member having spaced projections and a reamer comprising a reaming blade and a pair of L-shaped projections at the end opposite said blade with the latter receivable between the projections on said body member, said reamer having an inoperative position wherein said blade overlies said body member to receive protection from the body member and an operative position wherein said blade projects outwardly from said body member, locking means comprising key-hole slots in the projections of said body member having their rectangular ends directed inwardly toward said body member, an axle member extending laterally of said L-shaped projections of said reamer nonrotatably fixed in said projections and having portions of rectangular cross section engaging said key-hole slots, the rectangular portions having a thickness enabling the same to be received in the rectangular portions of said key-hole slots and a width slightly smaller than the diameter of the rounded portions of said key-hole slots, spring means urging the axle-forming member toward the rectangular end of said key-hole slots, and a U-shaped channel in said body member adapted to receive the L-shaped projections of said reamer when in operative position.

2. In a combination tube working tool and reamer comprising a body member having a base, an end and a recess opening through both the end and the base at the intersection thereof, wall portions of said body member forming the sides of the recess, said wall portions having key-hole slots therein positioned with rounded portions thereof near said end and narrow portions extending away from said end, an axle member mounted in said slots and extending between said wall portions, said axle member having a portion of rectangular transverse cross section at each end engaging said slots and being rotatable in the enlarged portions thereof and slidable longitudinally of said body member in the narrow portions of said slots, and a reaming portion, a locking portion comprising L-shaped projections fixedly mounted on said axle member in said recess adjacent said wall portions, said reamer being pivotally movable between inoperative position wherein said reaming portion overlies said body member and operative position wherein said reaming portion projects from said end of the body member, said body member having a U-shaped channel in said recess adapted to receive said L-shaped projections when said axle member is in the narrow portions of said slots to lock the reamer in operative position.

3. In a combination tube working tool and reamer comprising an elongated body member adapted to be held in the hand of a workman, said body member having a recess opening through one end and the base of said body member at a corner thereof, wall portions of said body member defining sides of said recess, each of said wall portions having a key-hole slot therein positioned with the circular portion outer-

most and the rectangular portion extending inwardly, an axle member mounted in said slots, said axle member having a portion of rectangular transverse cross section engaging said slots and being rotatable in the circular portions thereof and slidable longitudinally of said body member in the rectangular portions, a spring mounted on said body member and engaging said axle member to urge the axle member toward the rectangular portions of said slots, and a reaming blade, a locking portion comprising a pair of L-shaped projections each having a portion lying in the plane of said blade, said projections being fixedly mounted on said axle member in said recess adjacent said wall portions, said reamer being pivotally movable between inoperative position wherein said blade overlies said body member and operative position wherein said blade projects from said end of the body member, said body member having a U-shaped channel in said recess adapted to receive said L-shaped projections when the axle member is in the narrow portions of the keyhole slots resiliently to retain the reamer in either position, the base of the U-shaped channel being spaced from a wall of the recess to provide a shoulder preventing pivotal movement of said reamer out of operative position until moved longitudinally outwardly a distance permitting the L-shaped projections to clear said shoulder.

4. In combination, a tool body and a reamer pivotally mounted thereon, said tool body having a base, an end, and a recess opening through both the end and the base at the intersection thereof, wall portions of said body forming the sides of the recess, one wall of said recess having formed therein near the inner edge thereof an outwardly opening, transversely extending channel, each of said wall portions having an elongated slot therein extending at right angles to said channeled wall and positioned outwardly of said channeled wall and outwardly of the channel in said channeled wall, said reamer comprising a flat blade having a reaming portion and a mounting and locking portion, projections extending laterally of said blade from the mounting portion thereof adapted to be receivable between the wall portions of said body forming the sides of the recess, an axle member carried by said projections and extending at its ends into the elongated slots in said wall portions to permit of rotational as well as limited bodily movement of said reamer blade, a rearward extension of said reamer blade receivable with a snug fit in the channel in the recess wall when the blade is swung to operative position projecting outwardly from the tool body, and spring means mounted on said tool body and engaging said reamer to urge the same with its axle member at the inner end of said elongated slots.

5. In combination, a tool body and a reamer wherein said reamer has an inoperative position overlying said tool body to receive protection from the body and an operative position wherein it projects outwardly from said tool body, said tool body having a base, an end, and a recess opening through both the end and the base at the intersection thereof, wall portions of said body forming the sides of the recess, one wall of said recess having formed therein an outwardly opening, transversely extending channel, each of said wall portions having an elongated slot therein extending at right angles to said channeled wall and positioned outwardly of said channeled wall and at least as far outwardly of

the remaining wall of the recess as said channel, said reamer comprising a flat blade having a reaming portion and a mounting and locking portion, projections extending laterally of said blade from the mounting portion thereof adapted to be receivable between the wall portions of said body forming the sides of the recess, an axle member carried by said projections and extending at its ends into the elongated slots in said wall portions to permit of rotational as well as limited bodily movement of said reamer blade, a rearward extension of said reamer blade receivable with a snug fit in the channel in the recess wall when the blade is swung to operative position projecting outwardly from the tool body, and spring means mounted on said tool body and engaging said reamer to urge the same with its axle member at the inner end of said elongated slots, said lateral projections extending outwardly from said reamer blade beyond said axle member and forwardly from said axle member a distance such that the point of each projection most remote from said axle member is spaced therefrom by a distance greater than that between the inner end of each elongated slot and the channeled wall of the recess.

6. A pipe burring reamer for mounting in a recess in a tool body comprising a blade having an operative portion and a locking portion, an axle secured to the blade spaced laterally of the plane of the blade for mounting the blade in the

recess, said tool body recess having sides with elongated openings therein to receive the end portions of the axle to permit swinging movement and longitudinal movement of the blade relative to the tool body, said locking portion including a rearward extension of said blade, said tool body having a channel for receiving and closely embracing said rearward extension when the blade is extended outwardly from the tool body in operative position, a spring bearing against the axle to yieldingly urge the same inwardly of said elongated openings, and laterally projecting means on the axle side of said blade and forwardly of said axle in position to engage the tool body and cam said axle outwardly in said elongated opening as said blade is swung from inoperative to operative position.
